RAILWAY TRAFFIC CONTROLLING
APPARATUS

Frank H. Nicholson, Wilkinsburg, Pa., assignor
to The Union Switch & Signal Company,
Swissvale, Pa., a corporation of Pennsylvania

Application July 25, 1934, Serial No. 736,957
Renewed October 9, 1935

18 Claims. (Cl. 246—34)

My invention relates to railway traffic controlling apparatus, and more specifically to apparatus for controlling wayside and cab signals by means of coded track circuit current.

5 One feature of my invention is the provision of simple and inexpensive means for transferring from a normally effective source of coded track circuit energy to an auxiliary source of coded track circuit energy in case of failure of the normally effective source.

10 I will describe one form of apparatus embodying my invention, and will then point out the novel features thereof in claims.

15 The accompanying drawing is a diagrammatic view showing one form of apparatus embodying my invention.

20 Referring to the drawing, the reference characters 1 and 1^a designate the track rails of a section of track 2—3 normally supplied with current from a track transformer T located at one end of the section. Connected across the rails at the other end of the section is a direct current code-following track relay TR. When the rails of section 2—3 are supplied with coded unidirectional current and the section is unoccupied, relay TR follows the impulses of the code, alternately closing its contacts 4—5 and 4—6 at a rate determined by the code being received. Each time that front contact 4—5 closes, an impulse of direct current from a source which is not shown but which has the terminals B—C, is supplied to the upper half of the primary winding of the decoding transformer DT. Similarly, each time that back contact 4—6 closes, a direct current impulse in the reverse direction is supplied to the lower half of the primary winding. This operation of relay TR causes an alternating potential of the code frequency to be induced across the terminals of the secondary winding 28.

25 40 If the code being received by relay TR comprises current impulses recurring at the rate of 180 times per minute, for example, decoding relay F will be energized because of the selective tuning which is accomplished by means of the condenser 18 and reactor 19. The rectifier RF permits a direct current decoding relay to be used. Since the decoding relay H is energized from an untuned circuit, this relay will also be picked up on the 180 code. However, if the code comprises 45 current impulses recurring at the rate of 80 times per minute, for example, relay F will be deenergized, and relay H alone will be energized. Control of suitable signaling apparatus such as 50 wayside signals, and the selection of the code which is ordinarily applied to the section in the

rear of location 2 may be accomplished over contact fingers such as 7 and 8 of relays H and F, respectively, in well-known manner. The apparatus described so far is well known and is believed to require no further detailed description. 5

I shall next describe the code-feeding apparatus for the section 2—3.

The reference character CT designates a coding device or code transmitter energized from the source B—C and arranged to be in operation 10 at all times, so that contacts 180 and 80 thereof constantly close and open at the rate of 180 and 80 times per minute, respectively. The code selection apparatus is not shown in detail, but it will be understood that this portion of the apparatus functions in the usual and well-known manner whereby a circuit will be completed over one or the other of wires 9 or 10, as determined by traffic conditions in advance. For example, when the advance block is unoccupied, wire 9 20 will be closed and wire 10 will be open, whereas with the advance block occupied, wire 10 will be closed and wire 9 will be open.

25 At location 3 is an alternating current source having the terminals BX—CX, which source is used for energizing the track transformer T, as well as the alternating current power-off relay PO. The power-off relay is maintained energized as long as the source BX—CX remains effective. Normally, therefore, if the advance section 30 is unoccupied, the primary winding 13 of transformer T is supplied with alternating current periodically interrupted at 180 code over a circuit extending from one terminal BX of the source, contact 180 of transmitter CT, wires 9 and 35 11, front point of contact 12 of relay PO, and winding 13, to the other terminal CX of the same source. If the advance section is occupied, winding 13 will receive alternating current periodically interrupted at 80 code over this same circuit, with the exception that contact 180 and wire 9 will now be replaced by contact 80 and wire 10.

40 Considering first the function of the secondary winding 14, this winding will impress periodically 45 interrupted alternating current across the terminals of the full-wave rectifier R, whereby periodically interrupted pulsating unidirectional current will be caused to flow in the rails 1—1^a for energizing the track relay TR. Assuming that 50 the instantaneous polarity of the right-hand terminal of winding 14 is positive, then at that instant, current will flow over a circuit which includes element 28 of rectifier R, winding 15, wires 28 and 27, the track circuit, wires 21 and 22, and 55

element 23, to the left-hand terminal of winding 14. At the instant when the left-hand terminal of winding 14 becomes positive, the current will flow over a circuit which includes element 24, winding 15, wires 26 and 27, the track circuit, wires 21 and 22, and element 25, to the right-hand terminal of winding 14. It will be apparent, therefore, that both half-waves of the alternating current output of winding 14 are rectified.

Considering next the function of the secondary winding 15, this winding provides half-wave rectification only, its rectified half-wave output being superimposed on the rectified full-wave output of winding 14. The current path from winding 15, at the instant when the right-hand terminal of the winding is positive, includes wires 26 and 27, the track circuit, wires 21 and 22, and rectifier paths 25-28 and 23-24 in parallel. The combined output of windings 14 and 15 results in a wave of current in the rails 1 and 1^a, this wave being unidirectional in character for operating the track relay TR, and also having undulations or variations therein for effective control of locomotive-carried cab signaling equipment. That is, the rectified rail current impulses are all of one polarity so that the direct current track relay TR may be controlled thereby. However, these individual impulses entail also a variation of the current, so that considering a single impulse, at one instant the current is building up, and at another instant is dying down. Since the locomotive equipment is sensitive to a variation of the rail current, though not to the actual magnitude of this current, the locomotive equipment will respond to the above variations.

It will be understood that winding 15 alone is sufficient to provide both the unidirectional and varying character of the track circuit current. However, the use of winding 14 renders the system more effective, since the average value of the rail current as well as the magnitude of the variations therein are both increased thereby. Obviously, transformer T need not have independent primary and secondary windings, but may be of the auto-transformer type, if desired.

Should the alternating current source BX-CX fail for any reason, relay PO will immediately release, disconnecting winding 13 from the code transmitter contacts, and closing an energizing circuit for the code-repeater or auxiliary relay CR over the back point of contact 12 of relay PO. The circuit for relay CR may be traced from one terminal B of a standby source, one or the other of contacts 180 or 80 of transmitter CT as determined by traffic conditions in advance, wire 9 or wire 10, wire 11, back point of contact 12, wire 16, and the winding of relay CR, to the other terminal C of the source. The terminals B-C may be terminals of the standby source S, which is illustrated.

Since the circuit for relay CR includes a code transmitter contact, this circuit will be periodically interrupted at the proper code frequency, so that relay CR will follow the code and will reflect the operation of the transmitter CT. Each time that relay CR picks up, an impulse of direct current from the emergency source S will be supplied to rails 1 and 1^a, over the front contact 11 of relay CR. Therefore, relay TR will continue to operate, after source BX-CX fails, so that the wayside signaling apparatus will be effective to control the movement of trains, even though the cab signaling equipment may not function due to the absence of any alternating

current component in the code current supplied from source S. The source S and rectifier R are poled in such manner with respect to each other as to prevent a short-circuit on the source through winding 15 when contact 17 is closed. 5

As soon as current from source BX-CX is restored, relay PO will pick up, restoring coded alternating current to winding 13 of transformer T and opening the circuit for relay CR. As soon as relay CR releases, source S will be disconnected 10 at front contact 17, and the system will continue to operate in the normal manner described above.

If it is desired to incorporate broken-down insulated rail joint protection into the system, relay TR may be a two-position polarized code-following relay, biased to the position in which back contact 4-6 is closed when the relay is either deenergized or is energized with unidirectional current of reverse polarity, for example. Under this condition, rectifier R and source S 20 should be poled in such direction that unidirectional current of normal relative polarity will be supplied to the rails of section 2-3, both at such times as the main source BX-CX is active, and at such times as the emergency source 25 S is active. The rails of the block section in advance as well as in the rear of section 2-3 would, under the above condition, be normally supplied with unidirectional current of reverse relative polarity, so that if the block joints at 30 location 2 or 3 should break down, the incoming current from the adjoining block will be of improper polarity for picking up relay TR.

Due to the fact that the code-repeating relay CR remains normally deenergized, and is 35 called upon to operate only in the event of a failure of the main source BX-CX, this relay need not be designed and constructed for long life under repeated operations, and can be of relatively inexpensive construction. Furthermore, 40 it should be noted that due to the arrangement of windings 14 and 15, rectifier R, and source S, no relay contacts whatever are included in the normal circuit which feeds current to the rails 1 and 1^a. Due to the fact that contacts in 45 the track feed circuit are ordinarily called upon to carry currents amounting to several amperes, the consequent burning at these contacts may introduce resistance into the feed circuit, or shorten the life of the contacts, rendering the 50 operation of the system less reliable. Therefore, the apparatus disclosed eliminates the troubles ordinarily incident to the use of relay contacts in the track feed and provides a reliable and relatively simple and inexpensive system for taking care of power failures. It will be understood 55 that the novel features of my invention are not limited to a system of the code type, as the invention can be used, as well, in a system using uncoded current having both unidirectional and alternating components. 60

Although I have herein shown and described only one form of apparatus embodying my invention, it is understood that various changes and modifications may be made therein within 65 the scope of the appended claims without departing from the spirit and scope of my invention.

Having thus described my invention, what I claim is:

1. In combination, a section of railway track, a 70 trackway device controlled by energy received from the rails of said section and responsive to coded uni-directional current, wayside signaling apparatus controlled by said device, a main source of alternating current, a rectifier, means includ- 75

- ing said main source and said rectifier for at times supplying the rails of said section with varying unidirectional current for controlling said device as well as for controlling train-carried signaling apparatus, an auxiliary source of direct current, means for at other times supplying the rails of said section with current from said auxiliary source, and means for coding the current supplied to said rails in accordance with traffic conditions
10. In advance of said section.
2. In combination, a section of railway track, a direct current code-following track relay for said section, wayside signaling apparatus controlled by said track relay, a main source of alternating current, a rectifier, means including said main source and said rectifier for supplying the rails of said section with varying unidirectional current for controlling said track relay as well as for controlling train-carried signaling apparatus, an auxiliary source of direct current, means for supplying current from said auxiliary source to said rails effective upon the failure of said alternating current source, and a coding device for coding the current supplied to said rails.
25. In combination, a section of railway track, a direct current code-following track relay for said section, a main source of alternating current, a transformer having a primary winding energized from said main source and having a secondary winding, a full-wave rectifier having its input terminals connected across said secondary winding, means for supplying the rails of said section with current from the output terminals of said rectifier, an auxiliary source of direct current, an auxiliary relay, means controlled by said auxiliary relay effective upon the failure of said main source for supplying said rails with current from said auxiliary source, and a coding device for coding the current supplied to said rails.
40. In combination, a section of railway track, a direct current code-following track relay for said section, a main source of alternating current, a transformer having a primary and a secondary winding, a power-off relay energized from said main source, a circuit including a front contact of said power-off relay for energizing said primary winding from said main source, a full-wave rectifier having its input terminals connected across said secondary winding, means for supplying the rails of said section with current from the output terminals of said rectifier, an auxiliary source of direct current, an auxiliary relay, a circuit including a back contact of said power-off relay for energizing said auxiliary relay, means including a front contact of said auxiliary relay for supplying said rails with current from said auxiliary source, and a coding device for coding the current supplied to said rails.
55. In combination, a section of railway track, a direct current track relay for said section, a main source of alternating current, a transformer, a power-off relay energized from said main source, a circuit including a front contact of said power-off relay for energizing said transformer from said main source, a rectifier, means including said rectifier for supplying current from said transformer to the rails of said section, an auxiliary source of direct current, an auxiliary relay, means including a back contact of said power-off relay for energizing said auxiliary relay, and means including a front contact of said auxiliary relay for supplying said rails with current from said auxiliary source.
70. In combination, a section of railway track, a direct current track relay for said section, a main source of alternating current, a transformer having a primary and two secondary windings, a power-off relay energized from said main source, a coding device, means including a front contact of said power-off relay and a contact of said coding device for energizing said primary winding from said main source, a rectifier, means including said secondary winding and said rectifier for supplying current to the rails of said section, an auxiliary source of direct current, an auxiliary relay, means including a back contact of the coding device for energizing said auxiliary relay, and means including a front contact of said auxiliary relay for supplying said rails with current from said auxiliary source.
75. In combination, a section of railway track, a direct current track relay for said section, a main source of alternating current, a transformer having a primary and two secondary windings, a power-off relay energized from said main source, a coding device, means including a front contact of said power-off relay and a contact of said coding device for energizing said primary winding from said main source, a full-wave rectifier having its input terminals connected across one of said secondary windings, a circuit including the output terminals of said rectifier and the other of said secondary windings for supplying current to the rails of said section, an auxiliary source of direct current, an auxiliary relay, means including a back contact of said power-off relay and said contact of the coding device for energizing said auxiliary relay, and means including a front contact of said auxiliary relay for supplying said rails with current from said auxiliary source.

- coding device for energizing said auxiliary relay, and means including a front contact of said auxiliary relay for supplying said rails with current from said auxiliary source.
5. 11. In combination, a section of railway track, a main source of varying current, a transformer energized from said main source, a rectifier, means including said rectifier for supplying both full wave and half wave rectified current from 10 said transformer to the rails of said section, an auxiliary source of current, and means effective upon a failure of said main source for supplying said rails with current from said auxiliary source.
12. In combination, a section of railway track, 15 a main source of alternating current, a rectifier, means including said rectifier for supplying both full wave and half wave rectified current from said main source to the rails of said section, an auxiliary source of current, and means effective 20 upon a failure of said main source for supplying said rails with current from said auxiliary source.
13. In combination, a section of railway track, a source of varying current, a transformer energized from said source, and means including a 25 rectifier for supplying both full wave and half wave rectified current from said transformer to the rails of said section.
14. In combination, a section of railway track, a source of varying current, and means including 30 a rectifier for supplying both full wave and half wave unidirectional current from said source to the rails of said section.
15. In combination, a section of railway track, a source of varying current, a transformer having 35 an input winding energized from said source and having a first and a second output winding, and means including a rectifier connected with said two output windings so as to supply full wave rectified current to the rails of said section from said first output winding through said second output winding and to supply half wave rectified current to the rails of said section from said second output winding.
16. In combination, a section of railway track, a source of varying current, a transformer having a primary winding energized from said source and having a first and a second secondary winding, a full wave rectifier having its input terminals connected with said first secondary winding, a connection from one output terminal of said rectifier to one rail of said track, and a connection from the other output terminal of said rectifier through said second secondary winding 15 to the other rail of said track.
17. In combination, a section of railway track, a source of varying current, a transformer having an input winding receiving energy from said source and having a first and a second output winding, and means including a rectifier connected in parallel with said first output winding and in series with said second output winding for supplying both full wave and half wave rectified current to the rails of said section.
18. In combination, a section of railway track, a source of varying current, a transformer having an input winding receiving energy from said source and having a first and a second output winding, a full wave rectifier, a first circuit including said rectifier and said first output winding connected in parallel for supplying full wave rectified current to the rails of said section, and a second circuit including said rectifier and said second output winding connected in series for 30 supplying half wave rectified current to the rails of said section.
